UNITED STATES PATENT OFFICE.

FRANCIS W. McFARLAND, OF MARTINEZ, AND WILLIAM R. LONG, OF BAY POINT, CALIFORNIA.

SIGNAL FOR RAILROAD CROSSINGS.

Application filed October 28, 1927. Serial No. 228,763.

The invention forming the subject matter of this application relates to combined signals and gates for railroad crossings that are automatically actuated by the approaching 5 train.

The primary object of this invention is the provision of a combined crossing gate and railroad signal that is actuated by the approaching train so that the signal is conspicuous and provides an effective warning at about the level of the driver's eye, and at the same time functions as a gate, for obstructing the traffic side of the highway.

Another object of the invention is to provide a combination signal and gate which obstructs the right of way on a highway and to provide a longitudinal partition in the center line thereof for preventing any automobile or other vehicle to leave the traffic 20 side of the highway, thereby permitting the obstruction of the right of way leading toward the railroad tracks, nevertheless permitting unobstructed travel away from the railroad tracks.

A further object of the invention is to provide a signal light and a signal bell that functions at a time previous to the operation of the gate itself. The signal and the bell are also actuated by the approaching train.

Another object of the invention is to provide a combined crossing gate and railroad signal that is readily actuated by a train approaching from either direction on any one of the railroad tracks, and which is operating 35 during the full length of the travel of the train on the section of the track adjacent to the highway crossing. The period of operation of the signalling gate is readily determined by the length of the track sections connected into the signal system.

Another object of this invention is to provide a combined highway gate and crossing signal which is highly useful and simple in construction. Convenience of arrangement, lightness, and comparative inexpensive 45 of manufacture are further objects which having been borne in mind in the production and development of our invention.

Other objects of the invention, together 50 with the foregoing, will be set forth in the following description of the preferred embodiment of means for practicing the same, which is illustrated in the drawings accompanying and forming part of the specification. It is to be understood that we do not

limit ourselves to the embodiment disclosed in said description and the drawings as we may adopt variations of our preferred form within the scope of our invention as set forth in the claims.

The invention is clearly illustrated in the accompanying drawings, in which,

Figure 1, is a perspective front view of a railroad crossing showing the signals and gates arranged on the opposite sides of the railroad tracks, and the highway.

Figure 2, is a side elevation of the gate in the housing, showing the gate actuating mechanism in closed position,

Figure 3 is a front view of Figure 2 showing the slot in the housing through which the gate moves,

Figure 4 is a vertical section of the gate and the actuating mechanisms therefor,

Figure 5 is a sectional detail view of the auxiliary signal light and bell,

Figure 6 is a wiring diagram of the combined signal and gate.

Our device is installed at highway crossings denoted by the numeral 1, railroad tracks 80 are designated by the numeral 2. A partition 3 is provided on both sides of the crossings disposed at about the middle of the highway for separating the right of way for approaching vehicles so that the motor vehicles 85 are forced to keep their course on the right side of the highway. A crossing gate 4 is installed at each side of the crossing in the direction of the approaching traffic.

The gate 4 comprises a casing 5 in which 90 a vertical shaft 6 and a guide 7 are fixedly secured in bearings 8 and 9 respectively. Solenoids 10 are secured to the casing 5 and are insulated therefrom. Plungers 11 are actuated by the solenoids 10 and are slidable on

the shaft 8. Extension lugs 12 protrude from the plungers 11 and are guided by the guide rod 7. A plurality of bars 13 are pivotally secured to each other at the crossing points 14 and to the adjacent bars at the ends 15 thereof, forming a system of bars jointed in the manner of lazy tongs. The bars which are closest to the extension lugs 12 are also

pivotally secured to each other at the crossing point 14 and the ends thereof are pivotally secured to the ends of the extension lugs 12.

As it is shown in dotted lines in Figure 2 when the extension lugs are brought in a position closest to each other the whole system of the jointed bars 13 is pivoted around 110

the respective crossing points 14 and extends in the conventional manner so that the gate obstructs the traffic side of the highway 1. Of course, there are sufficient number of bars 13 provided, and of suitable length to form a gate which in the extended position thereof reaches across the right side of the highway close to the partition 3. The letters 16 forming the word "Stop" are secured to the center portion of the pivoted bar 13, each letter 16 is secured to a separate pair of crossing bars 13 so that when the gate is closed the stop signal also extends across the highway at the level of the gate. The gate is closed by the action of the solenoids 10. When said solenoids are charged the plungers 11 are drawn therein guided on the shaft 6, thereby moving the extension lugs 12 toward each other and extending the gate across the road. A spring 17 is provided in each solenoid 10, one end thereof bearing against the wall of the solenoid, the other end pressing against the plunger 11, so that when the electric current is disconnected and the solenoid demagnetized, the action of the spring 17 returns the plungers 11 to the original position thereof thereby opening the gate 13, as shown in Figure 1 and Figure 2.

Each of the railroad tracks 2 comprises two rails 18 and 19. The gate and the signals are actuated by the approaching train on either one of the tracks in the following manner. The solenoids 10 of each gate are directly connected to a terminal of the source 35 of the electromotive force, such as a generator or the like, not shown. The connection is effected through the wire 20. The other terminals of the solenoids 10 are connected to the rails 18. The rails 19 are directly connected to the other terminal of said generator or the like. The rail 18 and 19 are made of steel which is a conducting material and sufficient number of railroad sections are connected so as to form a continuous electric connection to a considerably large distance on either side of the railroad crossing. The length of the sections electrically charged may be arbitrarily chosen according to the local conditions and according to the necessity of the 50 period to elapse between the arrival of the train to the crossing and the closing of the gates. When the train reaches the electrically charged section of the railroad tracks 2 the electrical circuit between the rail 18 and the rail 19 is immediately completed by the 55 wheels of the train so that the electric current begins to flow through the circuit from the wire 20 to the solenoids 10 then to track 18 through the wheels of the train to the rail 19 then to the opposite terminal of the source 60 of the electromotive force. The current flowing through the solenoids 10 actuates the gate and the signal in a manner heretofore described. The signal lights of the letters 16 are also individually connected into

a parallel circuit to the solenoid circuit so that when the approaching train completes the electrical connection between the rails 18 and 19 the lights of the letters 16 are immediately actuated. It is preferable to make the letters 16 of the type of neon electric sign or any other very conspicuous light which may be seen at a distance and which readily attracts the attention of the drivers of motor vehicles.

In order to obviate the danger of any vehicle crashing into the gate, warning is given to the automobilists by means of a signal light 23 and a bell 24 disposed on opposite sides of the crossings turned towards the right of way of the approaching traffic at a distance from the crossing gate. The signal 80 23 and the bell 24 are actuated by a separate circuit which comprises the electrical connection 25 directly connected to a terminal of the light 23 and the bell 24, the other terminal thereof is secured to a line 26 connected to a rail 27. Another rail 28 is connected to the opposite terminal of the electro-motive force. The section of the rails to which the bell 24 and the light 23 are connected is insulated from the section of the rails operating the gate and the signal thereon. The length of these rail sections is arbitrarily 90 determined according to local conditions.

The housing 5 is so constructed as to completely shield the gate actuating mechanism. An extension casing 29 is preferably integral with the housing 5 and is of sufficient length to cover all the bars 13 when the gate is contracted. The extension casing 29 is narrower than the housing 5 providing an opening 30 of such a size that the gate is allowed to clearly move therethrough as shown in Figure 3.

A signal light 31, preferably of blue color is disposed on the housing and it is turned toward the approaching train. The light 31 is actuated by a switch 32 fixedly secured to the guide rod 7. The upper lug 12 is insulated from the rod 7 and carries a protrusion 33, which engages the switch 32, when the gate is closed as in Figure 2. A terminal 34 of said lug 12 is connected into the solenoid circuit while the switch is connected in series with terminal of the light 31, the other terminal of said light completes the circuit to the wire 20.

When the gate is completely closed the protrusion 33 closes the electric circuit through the switch 32 and actuates the blue light 31 indicating that the gate is closed. The light 31 may be disposed at any convenient point where it is readily noticed by the engineer of the approaching train, so that the engineer knows either that the gate is closed or that it failed to function. In the event of any trouble in the gate mechanism the absence of the blue light warns the engineer that the gate is out of order.

When a train approaches in either direction on the track the wheels on the train close the circuit of the signal light 23 and bell 24 through the rails 27 and 28, thereby giving fair warning to the driver of vehicles on the highway before the gate is closed. The train then passes on to the section of the track 2 which is connected to the solenoids 10 and closes the circuit of said solenoids and the 10 stop sign 17, thereby immediately actuating the gate and the stop light. In the event of any automobile being caught inside of the gate on the railroad tracks, the driver still has a chance to drive across the track to the 15 other section of the highway and to freely proceed on the highway because of the fact that the gates obstruct only the right side of the highway on the side of the approaching traffic while the opposite side thereof is entirely free from obstruction. It is evident 20 that a large number of accidents are avoided by leaving the right of way free on the opposite sides of the gates so as to permit the free travel of the vehicles away from the 25 railroad tracks. When the gate is fully extended the blue signals the engineer of the approaching train that the way is clear.

It will be recognized that a particularly simple device is provided to give fair warning to the drivers of motor vehicles on the highway at a point that is far enough from the railroad crossing to give the driver an opportunity for slowing down before the gate is closed. It is also to be noted that if the 30 driver passes the gate and the gate is closed behind the vehicle, the vehicle can still safely pass across the railroad tracks 2 and freely proceed on the unobstructed section of the highway on the opposite side of the crossing. The length of the electrically charged section 35 of the track 2 for operating the gate must be so determined as to give sufficient time to a vehicle to travel across the railroad track 2 after the gate is closed, although most of the time the auxiliary signals 23 and 24 must be sufficient warning for automobilists to slow 40 down before the gate is closed. The device is entirely automatic and is actuated by the approaching train and obviates the necessity of the manually operated railroad gates 45 which proved to be dangerous and ineffective in many ways. The timing of the signs and the gate is accurate, the operation thereof is positive. The signal lights and letters are 50 made very conspicuous by being extended across the road at about the level of the driver's eyes. It is not necessary for the driver to watch for the signals above or below the level of his eyes.

The arrangement of the gates heretofore 55 described greatly facilitates the regulation of the vehicle traffic at railroad crossings. The device provided to accomplish the automatic operation of the gates and signals by 60 means of the wheels of the approaching train,

combines light weight, and rapid movement with a ruggedness of construction and sufficient flexibility to readily adapt the same to varying local conditions.

Having thus described my invention what I now claim as novel and desire to secure by Letters Patent is:

I claim:

1. A gate at a crossing of a highway and a railroad track section; the gate comprising a housing, a highway obstruction, solenoids in said housing, and means to operatively connect said obstruction to the solenoids, said solenoids being in electrically operative relation to said track section and being actuated by a train thereon.

2. A gate at the crossing of a highway and a railroad track, the gate comprising a housing, a telescoping road obstruction, solenoids in said housing, and means to operatively connect said obstruction to said solenoids, said solenoids being electrically connected to said track so as to be actuated by an approaching train thereon.

3. A gate at the crossing of a highway and a section of railroad rails, comprising a housing, a telescoping highway obstruction, solenoids in said housing, and means on said solenoids for operatively engaging said obstruction for transversely extending and contracting the same on the right side of the highway; said solenoids being connected in series with one of said rails, the other rail being electrically charged, so as to be actuated by a train completing the connection between said rails.

4. A gate at the crossing of a highway and a section of railroad rails, comprising a housing, a telescoping highway obstruction, solenoids in said housing, means on said solenoids for operatively engaging said obstruction for transversely extending and contracting the same on the right side of the highway; said solenoids being connected in series with one of said rails, the other rail being electrically charged, so as to be actuated by a train completing the connection between said rails, and a signal light on said obstruction, movable therewith and connected in parallel to said solenoids.

5. A gate at the crossing of a highway and a section of railroad rails, comprising a housing, a telescoping highway obstruction, solenoids in said housing, means on said solenoids for operatively engaging said obstruction for transversely extending and contracting the same on the right side of the highway; said solenoids being connected in series with one of said rails, the other rail being electrically charged, so as to be actuated by a train completing the connection between said rails, a signal light on said obstruction, movable therewith and connected in parallel to said solenoids, a second section of rails, and insulated from said first section, and a secondary

signal, connected in series with one of said rails, the other rail being electrically charged; said secondary signal to be actuated by a train completing the connection between said rails previous to the operation of said gate.

6. A gate at the crossing of a highway and a section of railroad rails, comprising a housing, a telescoping highway obstruction, solenoids secured to the housing, plungers resiliently mounted in said solenoids; and means on said plungers for operatively engaging said gate; said solenoids being connected in series to one of said rails, the other rail being electrically charged, so as to be actuated by a train completing the connection between said rails, a signal light on said obstruction, movable therewith and connected in parallel to said solenoids, a second section of rails, and insulated from said first section, a secondary signal connected in series with one of said rails, the other rail being electrically charged; said secondary signal to be actuated by a train completing the connection between said rails previous to the operation of said gate, and a third signal visible from the direction of said rails, being connected in parallel in the solenoid circuit and being actuated by the closed gate.

7. A highway obstruction at the crossing of a section of railroad rails, said obstruction comprising a housing, a telescoping gate, solenoids secured to the housing, plungers resiliently mounted in said solenoids; and means on said plungers for operatively engaging said gate; said solenoids being connected in series to one of said rails, the other rail being electrically charged, said solenoids to be actuated by a train on the rails, completing the connection between said rails.

8. A highway obstruction at the crossing of a section of railroad rails, said obstruction comprising a housing, a telescoping gate, solenoids secured to the housing, plungers resiliently mounted in said solenoids; means on said plungers for operatively engaging said gate; said solenoids being connected in series to one of said rails, the other rail being electrically charged, said solenoids to be actuated by a train on the rails, completing the connection between said rails, and partition on the highway, said gate to be disposed on a side of the partition opposite the traffic approaching the railroad tracks.

In testimony whereof we affix our signatures.

FRANCIS W. McFARLAND.
WILLIAM R. LONG.
